UNITED STATES PATENT OFFICE.

HERBERT A. BOWEN, OF CHICAGO, ILLINOIS, ASSIGNOR TO NATIONAL DUMP CAR COMPANY, OF CHICAGO, ILLINOIS, A CORPORATION OF MAINE.

DUMP-DOOR-OPERATING MECHANISM.

1,112,593.

Specification of Letters Patent.

Patented Oct. 6, 1914.

Application filed October 18, 1910. Serial No. 587,691.

To all whom it may concern:

Be it known that I, HERBERT A. BOWEN, a citizen of the United States, residing at Chicago, in the county of Cook and State 5 of Illinois, have invented certain new and useful Improvements in Dump-Door-Operating Mechanism, of which the following is a specification.

My invention relates to dump cars and 10 has for its object the providing of improved mechanism for operating the dump doors.

My invention relates more particularly to the hopper types of cars which have sloping end walls leading to a central discharge 15 opening, though it may be applied to other forms of dump cars.

My invention is adapted to permit all of the doors to be operated from either side 20 of the car.

A further object of my invention is to provide a mechanism which will permit the operation of the doors on one side only of the car by an operator who may be standing 25 at either side of the car.

My improvements are related to doors which are hinged at the sides of the car and have their meeting edges at the center of the car, said doors being supported in 30 their closed positions by movable supporting shafts or members lying longitudinally of the car. My improvements, however, are applicable to other arrangements than the above.

My improvements comprise more specifically, ratchet bars having movements transversely of the car, said ratchet bars being adapted to engage the supporting shafts and cause movements thereof toward or away 40 from their door supporting positions. These ratchet bars are operated by means which can be actuated at either side of the car, and the direction of the movement produced may be controlled by the operator from that 45 side.

Other objects of my improvements will be made more apparent in the following specification, taken in connection with the accompanying drawings, and the novel elements and combinations thereof will be set forth in the claims.

In the drawings Figure 1 is a side elevation of a hopper type of dump cars with my improvements applied thereto. Fig. 2 55 is a cross section of the lower portion of

said car, taken substantially along the line 2—2 of Fig. 1 and the line 2—2 of Fig. 4. Fig. 3 is a horizontal section of a lower central portion of the car, taken substantially on the lines 3—3 of Fig. 4 and 3—3 of Fig. 2 with the dump doors and other portions of the mechanism omitted. Fig. 4 is a vertical section taken on the line 4—4 of Fig. 2. Fig. 5 is a vertical section of the central lower portion of the car, taken substantially along the line 5—5 of Fig. 2. Fig. 6 is an elevation of one of the guide plates through which the ends of the operating levers project. Fig. 7 is a detail of a portion of the operating lever. Fig. 8 is a side elevation 70 of the same. Fig. 9 is a sectional detail of the dump doors. Fig. 10 is a perspective view of the ratchet bars, detent bars, and counterweights shown removed from the car, in incomplete and diagrammatic form 75 to show their relation. Fig. 11 is a cross section on the line 11—11 of Fig. 3. Fig. 11^a is a cross section on line 11^a of Fig. 2. Fig. 12 is a detail showing the form of the ratchet teeth. 80

In the drawings I have preferred to illustrate my improvements in connection with a car of the hopper type constructed chiefly of steel. In the said car the side walls 10 are made of steel plates, and the sloping 85 end walls 11 are also made of steel plates suitably joined at their lateral edges to the side walls 10. The sloping plates 12 are attached to the side walls 10 at their upper edges and terminate in vertical portions 13 adjacent their lower edges, these vertical portions forming the side walls of a central discharge opening. The sloping end walls 11 are also provided with vertical portions 11^a near their lower edges, which serve as 90 vertical end walls for the said central discharge opening. These vertical portions 11^a terminate in flanges or lips 11^b, against which the dump doors close, as will be described later. 95

The central discharge opening is divided into two parts, which are in effect separate openings, by steel plates 14 and 15, which have sloping portions meeting at their upper edges. These plates 14 and 15 are joined 100 together at said edges by means of the flanges 18 and 19, through which are placed rivets or other suitable fastening devices. The lower portions 16 and 17 of these plates 14 and 15 are given a vertical position and 110

serve as walls for the two portions of the central discharge opening. These vertical portions 16 and 17 terminate at their lower edges in horizontal lips or flanges 16^a and 17^a. The dump doors 20—21 when in their closed positions bear against the under surfaces of the lips 11^b, 16^a, 17^a, &c.

The plates 14 and 15 are held rigidly in position by the angle bars 22 and 23, which extend transversely of the car and are secured to longitudinal frame members 24—25. Other longitudinal frame members 26—27 are attached to the lower edges of the side walls 10. Intermediate transverse members 28 extend from the member 24 to the member 27 and from the member 25 to the member 26.

The dump doors 20, 21, &c., are pivotally attached to the members 24, 25, at 29, 29^a. The doors 20—21 are provided with stiffening ribs 30, which are upwardly turned at their outer ends and serve as means for the attachment of the hinge members. These ribs 30 are provided with a sloping portion 31 which terminates in a horizontal portion 32 spaced from the body of the doors 20—21 by Z-bars 33, or the like. These Z-bars have horizontal flanges 35, to which the ribs 30 are secured, and similar horizontal flanges 34 by which they are secured to the bodies of the doors.

The ribs 30 rest upon the rollers 36, which are rotatively mounted upon the supporting shafts 37. Shafts 37 are preferably square and are provided with sleeves 38 having a square, axial opening fitted to the square shaft, and having a cylindrical outer surface to which the said rollers 36 are rotatively fitted. The doors are held in their closed positions by said rollers which bear upon the horizontal portions 32 of the ribs 30. When said rollers are moved away from this horizontal position, or outwardly from the center of the car, they roll along the inclined portions 31 and allow the doors 20 and 21 to drop. My invention is more particularly related to the means by which the shafts 37 are moved away from and returned to their normal door-supporting positions, said positions being shown in Fig. 9 and others.

The sleeves 38 rest upon the supporting bars 39, which have horizontal portions 39^a upon which the sleeves roll, as upon a track, and vertical end portions 39^b and 39^c by which they are rigidly attached to the car frame. The vertical portions 39^b are attached to the transverse angle bars 22 by suitable rivets or other fastening means 39^d. They are also attached to transverse plates 40, which have positions directly below the vertical legs 22^a of said angle bars and are secured to the vertical portions 16, 17 of the plates 14, 15. The lower edges of the plates 40 serve as means for guiding the sleeves 38, and hence the shafts 37, and they serve more

strictly as means for preventing the shafts rising out of contact with the supporting bars 39. These transverse plates 40 serve as continuations of the walls 16, 17 and complete the housing or protecting means for the greater part of the door-operating mechanism.

The sleeves 38 have gears 41 integral with or attached to them at their ends, the teeth of said gears meshing with teeth or pins 42 fixed to the supporting bars 39. The row of pins 42 on each bar 39 serves as a rack in which the gears 41 operate when rotating to cause a movement of the shafts 37 on said track bars 39. Each shaft also carries two ratchet wheels 43, 43^a, and 43^b, 43^c, which mesh with and are driven by ratchet bars 44, 44^a and 44^b, 44^c. The teeth of the two ratchet wheels 43, 43^a slope in opposite directions and mesh with the teeth of the ratchet bars 44, 44^a, which also slope in opposite directions and which are adapted to mesh with the teeth of their corresponding ratchet wheels. The teeth of the ratchet bar 44 are adapted to engage the teeth of the ratchet wheel 43 when moving toward the left, as viewed in Figs. 2 and 3, and to slip over said teeth into a position making a new engagement with said teeth when moving toward the right, as viewed in Figs. 2 and 3. The teeth of the ratchet bar 44^a are adapted to engage the teeth of the ratchet wheel 43^a when said ratchet bar moves toward the right, as viewed in Figs. 2 and 3, and to slip over said teeth into position to make a new engagement with said ratchet wheel when moving toward the left, as viewed in Figs. 2 and 3. The teeth of the ratchet bar 44^b are adapted to engage the teeth of the ratchet wheel 43^b when said ratchet bar is given a movement toward the left, as viewed in Figs. 2 and 3, and to slip over the teeth of said ratchet wheel into a position ready to make a new engagement with the ratchet wheel 43^b when moving toward the right, as viewed in Figs. 2 and 3. The teeth of the ratchet bar 44^c are adapted to engage the teeth of the ratchet wheel 43^c when the said ratchet bar is given a movement toward the right, as viewed in Figs. 2 and 3, and to slip over the teeth of the ratchet wheel 43^c when moving toward the left, as viewed in Figs. 2 and 3. The reciprocating movements of said ratchet bars are effected by means of levers 48, 48^a which are pivotally attached to the car body by means of a pin 47. These levers extend to the sides of the car within reach of the operator. A downwardly extending arm 46 is fixed to these levers and is pivotally attached to the above described ratchet bars 44, 44^a, 44^b, 44^c.

The ratchet bars are arranged in pairs 44 and 44^b forming one pair, 44^a and 44^c forming another pair, in such a manner that one ratchet bar only of each pair can be engaged

with its respective ratchet wheel at the same time. The ratchet bars 44 and 44^b are rigidly attached to a common center piece 44^d which is pivotally attached to the downwardly projecting arm 46. They thus constitute, in effect, a single bar and are made in separate pieces for constructive reasons only. The ratchet bars 44^a and 44^c also constitute a single bar in effect and are rigidly attached to a center piece 44^e, which is also pivotally attached to the downwardly projecting arm 46. The ratchet bars 44 and 44^b, as well as the bars 44^a and 44^c, are so attached to their center pieces 44^d and 44^e, respectively, that they have positions relative to each other, making angles of less than 180 degrees in order that both of said ratchet bars cannot make engagement with their respective ratchet wheels simultaneously. In other words, when one of the ratchet bars 44, for instance, is engaged with the ratchet wheels 43, the other ratchet bar 44^b must be free of its ratchet wheel 43^d. The center pieces 44^d and 44^e have an angular form with their hubs 44^f and 44^g located at the apexes of the angles. These hubs form the means for making a pivotal attachment with the arm 46, a pin 45 being inserted through said hubs and through the eyes 46^e, 46^f and 46^g at the lower extremity of the said arm 46.

The arm 46 is preferably of rectangular form, having a considerable width in the direction of the axes of the pins 45 and 47. Notches 46^e and 46^d in the lower portion of this arm 46 facilitate the attachment of the center pieces 44^d and 44^e. The arm 46 is provided with laterally extending wings 46^a and 46^b to which the levers 48, 48^a are riveted. The ratchet bars are preferably riveted to the center pieces 44^d, 44^e as shown at 44^h. The pin 47 is supported in bearings 51, 52, which are fixed to the plates 40^a, 17, and 40, 16.

The teeth of the pair of bars 44, 44^b all slope in the same direction, and the teeth of the pair of bars 44^a and 44^c all slope in one direction, but in the opposite direction to those of the other pair. All of the teeth on the pair of bars 44 and 44^b are adapted to cause rotation, and hence a movement of the shafts 37 toward the left, as viewed in Figs. 2 and 3. All of the teeth on the pair of bars 44^a and 44^c are adapted to cause a rotation, and hence movement of the said shafts 37 toward the right, as viewed in Figs. 2 and 3. One only, however, of the ratchet bars 44, 44^b can be in engagement with a ratchet wheel at a time, and the same is true with the pair of bars 44^a, 44^c. It will be observed that it is usually desired to move the shafts 37 in opposite directions at the same time. When it is desired to move the shafts 37 toward the center of the car and close the doors, the ratchet bar 44 will be placed in engagement with the ratchet wheel 43 and the ratchet

bar 44^c will be placed in engagement with the ratchet wheel 43^c. The other ratchet bars 44^a, 44^b will at this time be out of engagement with their respective ratchet wheels. A reciprocating movement of the ratchet bars under these conditions will cause the shafts 37 to be moved toward the center of the car. When it is desired to cause a reverse movement of the said shafts, the bars 44^a, 44^b will be moved into engagement with their respective ratchet wheels 43^a, 43^b and the bars 44, 44^c will be out of engagement with their respective wheels. A reciprocating movement of the bars under these conditions will cause an outward movement of the shafts 37.

When the shafts are being moved toward the center of the car it is desirable that they be held or detained at the ends of the steps in the movement, in order that they may not slip back while the ratchet bars are being moved into a new engagement with their respective ratchet wheels by the operator. The detaining means for the above purpose comprises ratchet bars 53, 54, which normally rest upon the ratchet wheels 43, 43^c at one side of the ratchet bars 44, 44^c.

Each of the ratchet wheels 43, 43^c is made of greater width than the other ratchet wheels 43^a and 43^b in order to accommodate the ratchet bars 53, 44 and 54, 44^c, respectively, which rest on each. These bars 53 and 54 are pivotally attached to the car frame by means of a pin 55. This pin is supported by brackets 56, 57 which are rigidly attached to the plates 40, 40^a. The bars 53, 54, therefore, have a stationary pivot. They are adjustable with relation to this pivot in order to enable them to accurately engage the teeth of the ratchet wheels 43, 43^c. It is desirable to adjust the said detent bars within the limits of the lengths of a single tooth, in order that the said detent bars may prevent the slipping back of the shaft 37 to an extent equal to a fractional part of one of the teeth of the ratchet wheels. This adjustment is effected by means of set screws 77, 78 which are inserted in the hubs 75, 76 on the said detent bars. These hubs are given an elongated form in order to allow the desired adjustment with relation to the pin 45.

The detent bars 53, 54 are adapted to prevent slipping back of the shafts 37 while they are being moved toward the center of the car, but it is unnecessary to provide means to prevent similar action when the shafts 37 are being moved away from the center of the car. In this outward movement the dump doors are being opened and the load discharged from the car and a free and unrestricted open movement is desirable.

During the outward movement of the shafts 37 it is desirable to have the detent

bars 53, 54 out of engagement with their respective ratchet wheels. It is also desirable when giving independent movements to the doors, such as is necessary when partly opening said doors or partly closing them, to lift said detent bars away from the ratchet wheels. In order to accomplish this lifting movement I have provided an upwardly turned end portion 53^a, which terminates in a horizontal portion 53^b at the end of the detent bar 53 and a similar arrangement at the end of the other detent bar 54, which are adapted to lift these detent bars when the ratchet bars 44, 44^c are lifted. I have provided projecting pins 73, 74 on said bars 44, 44^c, respectively, which lie directly beneath the ends 53^b, 54^b of said detent bars. These pins are spaced a sufficient distance from said ends 53^b, 54^b in their normal positions to permit the slight vertical oscillation of the ratchet bars while they are slipping over the teeth of the ratchet wheels. This spaced relation is such as will cause the said detent bars to be lifted entirely free of the ratchet wheel when the ratchet bars 44, 44^c are lifted to the much greater height that is necessary when reversing the mechanism and changing the direction of movement of the shafts 37. The detent bars will be lifted, when it is desired to move the shafts 37 outwardly and to dump the load. These detent bars may also be lifted by hand when the operator desires to effect a smaller movement of the parts.

In order to hold the bars in their proper position when engaged with the desired ratchet wheels, I provide weighted members 64, 65, 66 and 67. Beginning with the weighted member 64, it will be seen to be pivoted at 69 to the plate 40^a. A slot 68 is provided in said member 64 which has a horizontal position, when the ratchet bar 44 is placed in engagement with the ratchet wheel 43. A laterally projecting pin 60, integral with said bar 44, projects into the slot 68. This pin serves the purpose of lifting the weight 64 when the bar 44 is raised. A reciprocating movement of the bar 44 is not interfered with by the weight 64, because of the fact that the slot 68 permits a free movement of the pin 60 therein. The weight of the body 64, however, is fully effective in holding the ratchet bar 44 in engagement with the ratchet wheel 43. When the ratchet bar 44 is elevated the slot 68 assumes a position approximating the vertical and in this position the said weight 64 is supported almost entirely by the pin 69. In this position the bar 44 is free to remain in its elevated position and its reciprocating movement is not interfered with to any appreciable extent by said weight, because of the fact that the weight is free to oscillate about its pivotal support 69.

While the bar 44 is in its lower position,

such position being shown in the drawings in Figs. 2 and 10 more particularly, the weight 66 occupies an elevated position, because of the fact that the bar 44^b is elevated at the time that the bar 44 is in its lower position. The above remarks relating to the elevated position of the weight 64 apply also to the weight 66 in the position shown in said Figs. 2 and 10. It will be seen that when either of said bars 44, 44^b is placed in position the tendency of the weight 64, or 66 as the case may be, is to hold them in that position. The said weights will hold them in that position until the operator exerts sufficient force upon either of the ends 79 or 81 to reverse the said position.

In order to allow for the extra weight of the detent bar 53, which must be lifted at the same time that the bar 44 is lifted, I provide a greater weight in the body 66 than is given to the body 64. This difference in weight will be sufficient to balance the weight of the detent bar. An entirely similar arrangement is provided for the bars 44^a, 44^c, though of course in their reversed relation. All of the above remarks which apply to bars 44, 44^b and the weighted members associated with them, will apply to the ratchet bars 44^a, 44^c, and the weighted members 65, 67. In Fig. 10 the bars are shown separately in more or less diagrammatic form, in order to make their relations more clear than is possible in the general views of the drawings.

In Fig. 11 is shown a sectional view taken approximately on the lines 11—11 of Figs. 2 and 3. This section is taken substantially through the pivots 70 and 71 of the weights 66, 65. The pivot pins 70, 71 are shouldered in the plates 40, 40^a and the weights are held in position thereon by washers 70^a and 71^a. The pins are riveted at their ends over the said washers and also over the said plates. In this view the different thicknesses of the counterweights 65, 66 will be observed. The relations of the bars 44^b, 44^c to said weights will be seen, said parts being shown in section. The laterally projecting lugs or pins 61, 62 will be seen to project into said weights. The relation of the actuating lever 48^a to the said parts will be seen in this view.

In order to prevent an incomplete stroke of the levers 48, 48^a, and thus to prevent a slipping back of the shafts 37 to an extent equal to a fraction of the length of one of the teeth on the ratchet bars and thereby permitting one of the shafts 37 to gain upon the other and to reach its closed position ahead of the other, thereby causing an imperfect closing of one of the doors, I provide a full stroke mechanism in connection with said levers. This full stroke mechanism comprises lugs 83, 83^a projecting

laterally from the said levers 48, 48^a and preferably integral therewith, said lugs being adapted to coöperate with curved or segmental ratchet bars 84, 84^a. These ratchet bars are pivotally attached to the framework of the car at 85, 85^a in such manner that the weights of said ratchet bars tend to cause them to move inwardly toward the body of the car; for accomplishing this purpose the upper ends of the ratchet bars are given a right angular form as shown in the drawings. The inward movements in the ratchet bars are stopped by the plates 92, 92^a against which the extreme lower ends of said ratchet bars make contact. The projecting lugs 83, 83^a have sloping surfaces which cause them to easily slip over the inclined faces of the ratchet teeth 86 in the upward movement of the actuating levers 48, 48^a. In the downward movement of said levers, however, the said lugs have a tendency to engage the horizontal faces of said teeth and the downward movement is thereby arrested in the event that the said levers have not previously been carried to the upper extremities of their strokes. In order to prevent interference of the downward movement of either of the levers 48, 48^a after a complete upward stroke has been effected, a device is introduced for holding the ratchet bar 84 out of the path of the lugs 83. This device is moved into its operative position at the extremity of the upward movement of the levers. This device comprises the cam shaped member 88 which is pivotally attached to the ratchet bar 84 by means of the pin 89. The normal tendency of the member 88 is to assume a pendent position with its lower curved face 88^a in contact with the stop pin 90. The curved face 88^a enables the lever 48 to wedge or cam the member 88 into the position shown at the right in Fig. 2. In this position the extremity of the member bears upon the plate 92 and the ratchet bar 84 is thereby held in a position spaced from the said plate 92 and in such position that the teeth 86 will not interfere with the downward movement of the lug 83. The lower extremity of the ratchet bar 84 is provided with an inclined face 87 against which the lug 83 strikes at the lower extremity of its movement and pushes the said ratchet bar to its outermost position. This outward movement is a swinging movement having the pin 85 as a pivot and it will be seen that the member 88 will be drawn away from the plate 92 a sufficient distance to permit it to swing downwardly and free of said plate. The corresponding member 88^a at the left side of the car, as viewed in Fig. 2, is shown in the above described lower position.

It will now be seen that when the lug 83 begins its upward movement the ratchet bar 84 will be free to move inwardly and again rest against the plate 92 at its lower end. In view of the fact that one of the arms 48 is moving in opposite directions to the other arm 48^a throughout the operation of the mechanism, it will be seen that one or the other of the ratchet bars 84 or 84^a will be effective at all times in preventing an incomplete stroke of said levers.

The operation of my invention has already been frequently referred to and it will be further stated that when the operator wishes to dump the load in the car he will first manipulate the ratchet bars 44, 44^a, 44^b and 44^c in such a manner that the portions 44^a and 44^b are in contact with the ratchet wheels 43^a and 43^b, respectively. This he is able to do from either side of the car by means of the ends 79, 80 of the bars 44, 44^a, respectively, on one side of the car, or by means of the ends 81, 82 of the bars 44^b, 44^c on the other side of the car. These ratchet bars are yieldably held in the above described positions against ordinary displacing causes by the weights 67, 66. While manipulating the ends 79, 80 or the ends 81, 82 as above described, the detent bars 53, 54 are moved out of engagement with the ratchet wheels 43, 43^c and said detent bars will not then interfere with the rotation of said ratchet wheels nor hence with the outward movement of the door supporting shafts. The operator then imparts an oscillating movement to the levers 48, 48^a by means of either of the ends 58, 59 on either side of the car. This oscillating movement causes a reciprocating movement of the ratchet bars and those particular portions 44^a and 44^b which are engaged with the ratchet wheels 43^a and 43^b will be effective in causing a movement of the shafts. This movement will be outwardly as above described. As previously described, the operator will be unable to impart other than complete strokes to the said levers, because of the full stroke device comprising the ratchet bars 84, 84^a and the projecting lugs 83, 83^a.

When the operator wishes to close the doors he first manipulates the ratchet bars in an opposite manner to that previously described by means of the ends 79, 80 or 81, 82. When closing the doors he places the ratchet bar 44 in engagement with the ratchet wheel 43 and the ratchet bar 44^c in engagement with the ratchet wheel 43^c. By this movement the detent bars 53, 54 are allowed to drop into engagement with said ratchet wheels. These detent bars prevent slipping back of the door supporting shafts while the inward step by step movement is being effected. The ratchet bars in this inward movement are actuated in a similar manner to that previously described in connection with the dumping of the load. The operator imparts an oscillating movement

130

to the actuating levers 48, 48^a by means of the end 58 or 59 on either side of the car.

It will be observed that the operator can so manipulate the ratchet bars that only one of them will be in contact with one of the ratchet wheels, in which case the doors on one side only of the car may be operated. This result may be effected by placing either pair of ratchet bars 44, 44^b or 44^c, 44^e in 10 a mid-position in which neither of the ratchet bars of said pair is in contact with a ratchet wheel. In doing this it will be necessary for the operator to retain his hold upon an end 79, 80, 81 or 82 of the 15 particular ratchet bars which he wishes to hold in said mid-position.

It will be seen that when either of the weights 64, 65, 66 or 67 have an upright position their weight is in a much greater 20 degree thrown upon their pivot pins 69, 70, 71 or 72. When they are in their lowermost position, however, a much greater portion of the weight is thrown upon the laterally projecting pins 60, 61, 62 and 63. 25 Therefore, it will be seen that when the weights are moved to their lower positions they are very effective in retaining the ratchet bars in contact with the ratchet wheels against accidental displacing causes. 30 It will be further seen that when the counter-weights are in their upright positions they will oscillate easily upon their supporting pivots 69, 70, 71, 72 and will offer little resistance to the reciprocating 35 movements of said ratchet bars.

It will be further seen that the operator is able to partly or wholly open the doors on one side of the car or to give them incomplete movements in either direction by 40 first placing one of the ratchet bars in mid-position, out of contact with a ratchet wheel and then manipulating the levers 48, 48^a. If it is desired to open the doors on one side only, either of the detent bars 53 or 45 54 will be lifted by hand, according to which of the sides it is desired to open. The full stroke ratchet bars 84, 84^a may be moved out of the way by hand should it become necessary when oscillating the levers 50 48, 48^a to a less extent than their full strokes.

It will be seen that I have produced very convenient and effective mechanism for the various purposes described.

While I have described more or less precisely the details of construction, I do not wish to be understood as limiting myself thereto, as I contemplate changes in form and the proportion of parts and the substitution of equivalents as circumstances may 55 60 suggest or render expedient without departing from the spirit of my invention.

I claim:

1. In a car having a dump door, a shaft for holding said door in a closed position, a 65 ratchet wheel fixed to said shaft, and a

ratchet bar adapted to engage said wheel and to give said shaft a movement with relation to its supporting position, the teeth on said wheel being under-cut to prevent disengagement of the teeth of the ratchet 70 bar therefrom.

2. In a car having a dump door, a shaft for holding said door in a closed position, a ratchet wheel fixed to said shaft, and a ratchet bar adapted to engage said wheel 75 and to give said shaft a movement with relation to its supporting position, the teeth on said wheel being undercut and the engaging surfaces of the teeth on the ratchet bar having a backward slope to prevent dis- 80 engagement of said teeth.

3. In a car having a dump door, a shaft for holding said door in a closed position, a ratchet wheel fixed to said shaft, and a ratchet bar adapted to engage said wheel 85 and to give said shaft a movement with relation to its supporting position, the teeth on said wheel having curved faces, and the engaging surfaces of the teeth on the ratchet bar having a backward slope to prevent dis- 90 engagement of said teeth.

4. In a car having a dump door, a supporting shaft for said door, a reciprocating ratchet bar adapted to give said shaft a movement with relation to its supporting position, 95 and means for retaining during the return stroke of said bar, said shaft in position at the end of each advancing stroke of the reciprocating movement of the bar.

5. In a car having a dump door, a supporting shaft for said door, a ratchet wheel fixed on said shaft, a reciprocating ratchet bar adapted to engage said wheel and to give it a rotary motion when reciprocated, means by which the rotation of said shaft 100 causes its movement with relation to its supporting position, and means for retaining during the return stroke of said bar, said shaft in position at the end of each advancing stroke of the reciprocating movement of the bar. 105

6. In a car having a dump door, a supporting shaft for said door, a ratchet wheel fixed on said shaft, a reciprocating ratchet bar adapted to engage said wheel and to give it a rotary motion when reciprocated, 110 means by which the rotation of said shaft causes its movement with relation to its supporting position, and a detent bar having teeth adapted to engage said ratchet wheel and prevent its rotation in the opposite direction to that produced by said first named ratchet bar.

7. In a car having a dump door, a supporting shaft for said door, a ratchet wheel fixed on said shaft, a reciprocating ratchet 115 bar adapted to engage said wheel and to give it a rotary motion when reciprocated, means by which the rotation of said shaft causes its movement with relation to its supporting position, a detent bar having teeth 120

adapted to engage said ratchet wheel and prevent its rotation in the opposite direction to that produced by said first named ratchet bar, and means for adjusting said detent bar 5 with relation to the engagement of its teeth with the teeth of the ratchet wheel and with relation to the teeth of said ratchet bar.

8. In a car having a dump door, a supporting shaft for said door, a ratchet bar 10 adapted to give said shaft a movement with relation to its supporting position, a detent member for said shaft, and means by which said ratchet bar may cause said detent member to become operatively disengaged from 15 said shaft when said ratchet bar is operatively disengaged from said shaft.

9. In a car having a dump door, a supporting shaft for said door, a ratchet bar adapted to give said shaft a movement with 20 relation to its supporting position, and means actuated by the operator and pivotally attached to said ratchet bar for imparting a reciprocating movement to said bar.

10. In a car having a dump door, a supporting shaft for said door, a ratchet bar 25 adapted to give said shaft a movement with relation to its supporting position, and means pivotally attached to the car frame and to said ratchet bar for imparting a reciprocating movement to said bar.

11. In a car having a dump door, a supporting shaft for said door, a ratchet bar adapted to give said shaft a movement with 30 relation to its supporting position, and means pivotally attached to the car frame and to said bar, and capable of being actuated by the operator from either side of the car for imparting a reciprocating movement to said ratchet bar.

40 12. In a car having a dump door, a supporting shaft for said door, a ratchet bar adapted to give said shaft a movement with relation to its supporting position, means pivotally attached to the car frame and to 45 said bar, and capable of being actuated by the operator from either side of the car for imparting a reciprocating movement to said ratchet bar, and a detent member pivotally attached to the car frame and adapted to engage 50 said shaft.

13. In a car having a dump door, a supporting shaft for said door, a ratchet bar adapted to give said shaft a movement with relation to its supporting position, means 55 pivotally attached to the car frame and to said bar, and capable of being actuated by the operator from either side of the car, for imparting a reciprocating movement to said ratchet bar, a detent member pivotally attached to the car frame and adapted to engage 60 said shaft, and means by which said detent member may be operatively disengaged from said shaft when said ratchet bar is disengaged therefrom.

65 14. In a car having a plurality of dump

doors, reciprocating supporting shafts for said doors, a ratchet bar having separate series of teeth adapted to engage and actuate said supporting shafts, one only, at a time, with relation to their supporting positions, and means for imparting a reciprocating movement to said ratchet bar. 70

15. In a car having a plurality of dump doors, reciprocating supporting shafts for said doors, a ratchet bar having separate series of teeth adapted to engage and actuate said supporting shafts respectively, one only, at a time, with relation to their supporting positions, said ratchet bar being movable to a position wherein another of said series of teeth on said bar is adapted to engage and give a movement to another of said supporting shafts respectively, and means for imparting a reciprocating movement to said ratchet bar. 75

16. In a car having a plurality of dump doors, reciprocating supporting shafts for said doors, a ratchet bar having separate series of teeth adapted to engage and actuate said supporting shafts respectively, one only, at a time, with relation to their supporting positions, said ratchet bar being movable to a position wherein another of said series of teeth on said bar is adapted to engage and give a movement to another of said supporting shafts respectively, and a detent member for one of said shafts, and means for imparting a reciprocating movement to said ratchet bar. 80

17. In a car having a plurality of dump doors, reciprocating supporting shafts for said doors, a ratchet bar having separate series of teeth, each series adapted to engage and actuate one of said supporting shafts respectively with relation to its supporting position, said ratchet bar being movable to a position wherein another of said series of teeth on said bar is adapted to engage and give a movement to another of said supporting shafts respectively, a detent member for one of said shafts, means whereby said detent member will be operatively disengaged from said shaft when said ratchet bar is disengaged therefrom, and means for imparting a reciprocating movement to said ratchet bar. 100 105 110 115

18. In a car having a plurality of dump doors, reciprocating supporting shafts for said doors, and a ratchet bar having separate series of teeth adapted to engage and actuate said supporting shafts, one only, at a time, with relation to their supporting positions, and means pivotally attached to said ratchet bar and to said car frame for imparting a reciprocating movement to said bar. 120

19. In a car having a plurality of dump doors, reciprocating supporting shafts for said doors, a ratchet bar having separate series of teeth adapted to engage and actuate said supporting shafts, one only, at a time, 125 130

- with relation to their supporting positions, and means capable of being operated from either side of the car for giving a reciprocating movement to said ratchet bar.
20. In a car having a plurality of dump doors, reciprocating supporting shafts for said doors, a ratchet bar having separate series of teeth adapted to engage and actuate said supporting shafts, one only, at a time, with relation to their supporting positions, said ratchet bar being movable to positions wherein it will engage and actuate one or the other of said shafts at the will of the operator, means for resisting displacement of said bar from said positions, and means for imparting a reciprocating movement to said ratchet bar.
21. In a car having a plurality of dump doors, reciprocating supporting shafts for said doors, a ratchet bar having separate series of teeth in different portions thereof adapted to engage and actuate said supporting shafts, respectively, one only at a time, with relation to their supporting positions, said ratchet bar being movable to positions wherein it will engage and actuate one or the other of said shafts at the will of the operator, weighted members pivotally attached to the car frame, one of which is placed adjacent each of said series of teeth and adapted to bear upon the respective portions of said bar with different pressures, the greater pressure being exerted upon the portion of said bar which is engaged with its respective ratchet wheel, and means for imparting a reciprocating movement to said ratchet bar.
22. In a car having a plurality of dump doors, reciprocating supporting shafts for said doors, a ratchet bar having separate series of teeth adapted to engage and actuate said supporting shafts, one only at a time with relation to their supporting positions, said ratchet bar being movable to positions wherein it will engage and actuate one or the other of said shafts at the will of the operator, a detent member for one of said shafts, means by which said ratchet bar may move said detent member out of engagement with its respective shaft, means for resisting disengagement of said bar from the particular shaft with which it may be engaged, said resisting means being adapted to exert less resistance to the movement of said bar when disengaging said detent member, and means for imparting a reciprocating movement to said ratchet bar.
23. In a car having a plurality of dump doors, reciprocating supporting shafts for said doors, a ratchet bar having separate series of teeth adapted to engage and actuate one or the other respectively of said supporting shafts at the will of the operator, means for resisting disengagement of said bar from said shaft, a second ratchet bar like said first named bar except that its teeth are oppositely sloped and adapted to engage and actuate the shaft not engaged by said first named bar in the opposite direction to said first named shaft, means for resisting disengagement of said second named bar from said shaft, and means for imparting a reciprocating movement to said bars.
24. In a car having a plurality of dump doors, reciprocating supporting shafts for said doors, a ratchet bar having separate series of teeth adapted to engage and actuate said supporting shafts, one only, at a time, with relation to their supporting positions, said ratchet bar being movable to positions wherein it will engage and actuate one or the other of said shafts at the will of the operator, means for resisting displacement of said bar from said positions, a second ratchet bar like said first named bar except that its teeth are oppositely sloped and adapted to engage and actuate the shaft not engaged by said first named bar in the opposite direction to said first named shaft, means for resisting disengagement of said second named bar from said shaft, means for imparting a reciprocating movement to said bars, and means for preventing incomplete strokes of said last named means.
25. In a car having a plurality of dump doors, supporting shafts for said doors, a ratchet bar adapted to give said shafts reciprocating movements with relation to their supporting positions, means capable of being operated from either side of the car for actuating said bar, and means for preventing incomplete strokes of said actuating means.
26. In a car having a dump door, a supporting shaft for said door, a ratchet bar adapted to give said shaft reciprocating movements with relation to its supporting position, and means for preventing incomplete strokes of said ratchet bar.
27. In a car having dump doors, movable supporting members for holding said doors in their closed positions, actuating means for said members pivotally mounted on the car frame adjacent the center thereof and operable at either side of the car, and reciprocating means moved by said actuating means for actuating and moving said members with relation to their supporting positions.
28. In a car having dump doors, movable supporting members for holding said doors in their closed positions, actuating means pivotally attached to the car frame at the center thereof and operable at either side of the car, and reciprocating means moved by said actuating means for moving said members with relation to their supporting positions, said reciprocating means being adjustable for reversing the direction of movement of said members at the will of the operator.
29. In a car having dump doors, movable

- supporting members for holding said doors in their closed positions, actuating means pivotally attached to the car frame at the center thereof and operable at either side of the car, reciprocating means moved by said actuating means for moving said members with relation to their supporting positions, said reciprocating means being adjustable at either side of the car for reversing the movement of said members.
30. In a car having dump doors, movable supporting members for said doors, actuating means pivotally attached to the car frame between the sides thereof and having an oscillatory movement, and means by which said oscillatory movement may effect an intermittent movement of said supporting members with relation to their supporting positions.
- 20 31. In a car having dump doors, movable supporting members for said doors, actuating means pivotally attached to the car frame between the sides thereof having an oscillatory movement, and means by which said actuating means may impart an intermittent movement to said supporting members with relation to their supporting positions, said means being adapted to reverse the direction of movement imparted to said members at the will of the operator.
32. In a car having dump doors, movable supporting members for said doors, actuating means pivotally attached to the car frame between the sides thereof having an oscillatory movement, said actuating means being operable from either side of the car, and means by which said oscillatory movement may effect an intermittent movement of said supporting members with relation to their supporting positions.
- 40 33. In a car having dump doors, movable supporting members for said doors, actuating means pivotally attached to the car frame between the sides thereof having an oscillatory movement, said actuating members being operable from either side of the car, and means by which said actuating means may impart an intermittent movement to said supporting members with relation to their supporting positions, said means being adapted to reverse the direction of movement imparted to said members at the will of the operator.
- 50 34. In a car having dump doors, movable supporting members for holding said doors in their closed positions, actuating means pivotally attached to the car frame at the center thereof and operable at either side of the car, reciprocating means moved by said actuating means for moving said members with relation to their supporting positions, said reciprocating means being adjustable for reversing the direction of movement of said members at the will of the operator, and means for retaining said reciprocating means in its adjusted position.
35. In a car having dump doors, movable supporting members for said doors, oscillatory actuating means pivotally attached to the car frame and reaching to either side, and means by which said actuating means may move said supporting members with relation to their supporting positions.
- 25 36. In a car having dump doors, movable supporting members for said doors, actuating means pivotally attached to the car frame and reaching to either side, means by which said actuating means may move said supporting members with relation to their supporting positions, and means for reversing the effect of said last named means on said supporting members.
37. In a car having dump doors, movable supporting members for said doors, actuating means pivotally attached to the car frame and reaching to either side, means by which said actuating means may move said supporting members with relation to their supporting positions, means for reversing the effect of said last named means on said supporting members, and means for retaining said reversing means in its reversed condition.
38. In a car having dump doors, movable supporting members for said doors, reciprocating means adapted to give said shaft a movement with relation to its supporting position, a single means pivotally attached to the frame of the car between the sides thereof and operable from either side of the car for actuating said reciprocating means.
- In testimony whereof, I have subscribed my name.

HERBERT A. BOWEN.
